UNITED STATES PATENT OFFICE.

EDWARD C. D'YARMETT, OF MUSKOGEE, OKLAHOMA.

CENTRIFUGAL PUMP FOR COMPRESSION AND VACUUM.

1,310,116.

Specification of Letters Patent.

Patented July 15, 1919.

Application filed January 29, 1916. Serial No. 74,982.

To all whom it may concern:

Be it known that I, EDWARD C. D'YARMETT, a citizen of the United States, residing at Muskogee, in the county of Muskogee and 5 State of Oklahoma, have invented new and useful Improvements in Centrifugal Pumps for Compression and Vacuum, of which the following is a specification.

My invention relates to centrifugal pumps, 10 and has as its object to provide a device wherein a liquid medium, such as mercury, is impelled by centrifugal force to compress a fluid medium of less density, such as air, or to exhaust a space of the fluid medium 15 which it contains.

Other objects of my invention are to provide a device wherein a gas, or the like, may be quickly, highly and economically compressed; to provide a device wherein a fluid 20 having a relatively low specific gravity is compressed by a liquid of greater density (herein termed the active liquid), the active liquid being intermittently forced through openings or passages in a revolving member and acting as liquid pistons therein to force the air or other fluid to be compressed from said passages and compress the same in a suitable chamber; to provide means for regulating the amount of active liquid admitted to the passages in the revolving member; to provide a device wherein the pressure of the compressed fluid may be easily and readily varied; to provide a device which is positive and efficient in action, 30 economical to operate, which may be constructed at relatively low cost, and wherein leakage is prevented.

The above and other objects of my invention are obtained by the structure described 40 in the following specification and shown in the accompanying drawings, wherein—

Figure 1 is a vertical section showing one embodiment of my improved device.

Fig. 2 is a top plan view of the device 45 shown in Fig. 1, one-half thereof being shown in elevation, and the other half in section.

Fig. 3 is a side elevational view of an impeller wheel mounted on a horizontal axis.

50 Fig. 4 is a horizontal sectional view taken on line 4—4, Fig. 3.

Fig. 5 is a fragmentary sectional view showing another embodiment of my improved centrifugal pump or compressor.

55 Referring to the drawings, wherein like numerals represent like parts in the several

views, 10 designates a body portion of any suitable construction, but which is preferably formed of two somewhat similar castings 11 and 12 secured together by any suitable means such as by bolts, and resting on or supported by legs or feet 13. The castings 11 and 12 when secured together provide a chamber 14 for the impeller wheel to be described. The chamber 14 terminates in 60 an annular compression chamber 15 in which the air or other fluid operated upon is compressed, the chamber being provided with an outlet passage 16 to which may be connected a pipe, or the like, leading to a place of 65 storage (not shown) and said pipe will be provided with a check valve to prevent the compressed fluid within the place of storage from escaping when the pump or compressor is shut down. About the compression chamber 15 is a water jacket 17, the water in 70 which absorbs the heat generated during the compression of the fluid, so that the temperature of the fluid remains substantially constant, and a larger volume of fluid may be 75 compressed at a given temperature, than if the water jacket were omitted. Immediately below the compression chamber 15 is an annular space 18 having communication with the chamber 15, by means of spaced-apart 80 vertical ports 19 and adapted to receive through these ports the active liquid which passes into the compression chamber from the impeller wheel.

Mounted upon the body portion 10 is a 90 cylindrical-like casing 20 having a fluid inlet or passage 21 and at one side a storage receptacle 22 adapted to receive the active liquid from the annular space 18 by means of a pipe 23, which pipe is provided with a 95 suitable valve 23'. In the lower portion of the casing 20 is an annular distributing passage 24 communicating with the receptacle 22 by means of a port 25. The annular passage 24 is provided with one or more discharge openings or nozzles 26, preferably four, spaced apart at an angle of ninety degrees. The nozzles 26 are provided with needle valves 27 which are received in screw-threaded openings through the casing 20. 100 By turning the valves, longitudinal movement is imparted to the same, and the flow of active liquid from the distributing passage 24 to the nozzle or nozzles is regulated as will be readily understood. I preferably 105 use four nozzles 26 placed at ninety degrees apart, but it is to be understood that any

suitable number of nozzles may be used, and that any suitable means for regulating the flow through the nozzles may be adopted.

Passing through a suitable bearing 28 in 5 the upper portion of the casing 20 is a vertically disposed drive-shaft 29, the lower end of which is provided with a suitable ball step-bearing 30 disposed in the bottom portion of the body 10. The step-bearing 10 30 has a step-bearing foot 31, and by means of an annular nut 32, the bearing may be adjusted relative to the shaft.

Mounted upon the lower end of the shaft 29 and fixed thereto is the impeller wheel 33, which preferably is disposed in a horizontal plane. The wheel is provided upon 15 its upper face and adjacent the hub 34 with an annular groove or recess 35 and opening into and radiating from the recess is a plurality of through openings or passages 36 which extend to the outer periphery of 20 the wheel and discharge into the compression chamber 15. The passages 36 may be straight or curved, and, if desired, they may 25 extend at an angle to the radii of the wheel as shown in Fig. 2. The annular groove 35 is positioned beneath the outlet ends of 30 the discharge nozzles 26 leading from the distributing passage 24. Extending from 35 the opposite faces of the wheel adjacent the outer periphery thereof are annular flanges 37 which engage in rabbeted recesses 38 in the body 10, so that an air-tight joint 40 is substantially obtained between the body 35 and the impeller wheel 33. The portion 10 and the impeller wheel 33. The inner peripheries of the annular flanges 37 are screw-threaded to receive annular rings 39, the outer surfaces of the rings being 45 beveled as at 40, to correspond to the beveled faces 41 on the casting 12. By adjusting the rings 39 relative to the wheel 33, frictional engagement between the faces 40 and 41 may be varied so that a fluid-tight joint is insured, which prevents the 50 escape of the compressed fluid from the compression chamber 15 to the chamber 14.

It is believed that the operation of my device will be readily understood from the above description; the drive shaft 29 is 55 driven by any suitable means and the impeller wheel 33 revolved therewith. The needle valves 27 are regulated to permit the active liquid, such as mercury, to flow from the distributing passage 24 through 60 the discharge nozzles 26 into the annular groove 35. The active liquid is split up into small plugs or globules, which act as pistons within the passages 36 in the wheel 33, and due to centrifugal force, they are 65 propelled outwardly toward the periphery of the wheel, and the gas or fluid to be compressed is forced from these passages into the compression chamber 15 from whence it passes outwardly through the outlet 16. The active liquid during the op-

eration of my device passes from the receptacle 22 through the port 25, distributing passage 24, nozzles 26, and through passages 36 in the wheel into the compression chamber 15, thence by means of ports 19 70 to the annular space 18. The pressure within the chamber 15 acts upon the surface of the active liquid, so that the same is forced through the pipe 23, valve 23', and back to the storage receptacle 22. Thus 75 the active liquid passes in a circuitous route and may be used any number of times, the operation of the wheel itself being sufficient to force the active liquid back to the storage receptacle. 80

It will be noted that the active liquid passes directly into the passages 36 and is forced outwardly therein by centrifugal force. The annular groove 35 is not flooded by or submerged in the active liquid, but a 85 sufficient amount of active liquid only is admitted to the groove to form liquid pistons at predetermined intervals within the passages 36. The passages are alternately filled with a definite amount of active liquid, 90 and a definite amount of the fluid acted upon, and preferably when one piston of active liquid is just leaving one of the passages a second piston of liquid is just entering the same, so that the fluid within the 95 chamber 15 cannot escape back through the passages 36.

In Figs. 3 and 4, I have disclosed an impeller wheel which is mounted upon a horizontal axis instead of a vertical axis as is 100 shown in the preceding figures. The impeller wheel 33' is mounted upon a horizontal axis or shaft 29', and, of course, is inclosed in a casing 10 similar to that heretofore described. The passages 36' radiate 105 from the annular groove 35', which groove is slightly undercut to prevent the active liquid from flowing over the face of the wheel. While I have disclosed but one nozzle, it is, of course, to be understood that 110 any number of nozzles may be provided in this embodiment of my invention.

In Fig. 5, I have disclosed a further embodiment of my invention wherein the active liquid is returned from the annular compression chamber to the inner ends of the radiating passages by gravity. In this figure, 29'' designates a vertical shaft to which is secured the impeller wheel 33'' having upwardly and outwardly inclined radiating passages 36''. The compression chamber 15'' is inclined upwardly and is somewhat elongated, and is curved downwardly at its upper or outer portion to provide an annular well 42. A pipe 43 passes through the casing 10'' and is connected at one end to the annular well, its inner end serving as a nozzle which is positioned immediately above the groove 35''. When the impeller wheel is revolved, the active liquid passes 125 130

through the passages 36" and due to centrifugal force, after leaving the passages flies through the compression chamber and collects in the well 42 from which it is conducted by means of the pipe 43, and due solely to gravity, to the groove 35", and thus the active liquid follows a circuitous path, being propelled outwardly by centrifugal force, and being returned by gravity to the groove 35".

I preferably use as an active liquid, mercury, but, of course, any other suitable liquid may be used, and while my compressor is particularly adapted to compress air, it may also be used to compress any other fluid, whether the same be in gaseous or liquid form.

By varying the speed of the impeller wheel, and regulating the valves in accordance with the speed or velocity of the wheel, the pressure of the compressed fluid obtained in the compression chamber may be varied, a high speed of the wheel obtaining a high pressure.

While I have described and shown my device as a compressor and to be used in compressing liquids or gases, it is to be understood that my device is also adapted to be used as a vacuum pump. It will be readily seen that the passage or space 21 within the cylindrical casing 20 would be exhausted of air or fluid if the inlet thereto were closed. A vessel, or the like, may be connected to the inlet of the casing 20, and the fluid content drawn therefrom upon the operation of the pump.

It is to be understood that my invention is susceptible of various modifications and changes which would be within the spirit of the invention without departing from the scope of the following claims.

What I claim is:—

1. In combination, a rotary member having radiating passages, a hub integral with the rotary member and forming a thrust bearing seat for the rotary member, a compression chamber into which the passages discharge, an annular groove in the rotary member about its axis of rotation from which the passages radiate, a reservoir for storing the active liquid above said rotary member, nozzles for discharging the active liquid from the reservoir into the annular groove, means for regulating the flow of said liquid through the nozzles, and means for admitting the fluid to be acted upon to said groove, the active liquid upon rotation of the rotary member being impelled by centrifugal force into the passages and forming liquid pistons therein to force the fluid acted upon therefrom and into the compression chamber.

2. In combination, a rotary member having radiating passages, a hub integral with the rotary member and forming a thrust

bearing seat for the rotary member, a compression chamber into which the radiating passages discharge, an annular groove in the rotary member about its axis of rotation from which the passages radiate, means for directing a predetermined quantity of active liquid to said groove, and means for admitting fluid to be acted upon to said groove, the active liquid upon rotation of the rotary member being impelled by centrifugal force into the passages and forming liquid pistons therein to force the fluid acted upon therefrom and into the compression chamber.

3. In combination, a body portion having a main chamber and a compression chamber about the main chamber, a rotary member within the main chamber having passages which discharge into the compression chamber, means for admitting a stream of active liquid to the passages, and removable sealing rings adjacent the outer edges of the rotary member and attached thereto for preventing communication from the compression chamber to the main chamber.

4. In combination, a rotating wheel having radiating passages therein, a body portion having a main chamber to receive the wheel, and an annular chamber into which the passages discharge, means for admitting predetermined amounts of an active fluid to the inner ends of the passages, rings adjustably connected to said wheel and adapted to frictionally engage the walls of said body portion to prevent escape of the fluid from the annular chamber and the main chamber.

5. In combination, a rotary wheel having radiating passages therein, a body portion having a main chamber to receive the wheel and a compression chamber into which the passages discharge, means for admitting an active liquid to the inner ends of the passages, annular flanges on said wheel adjacent the periphery thereof, rings screw-threaded on said flanges and adjustable relative thereto, said rings being adapted to frictionally engage the walls of the body portion to prevent escape of the fluid from the compression chamber to the main chamber.

6. In combination, a rotary member having radiating passages therein, a compression chamber into which said passages discharge, means for admitting a predetermined amount of an active liquid to the inner end of each of the radiating passages, an annular collection chamber for the active liquid below the compression chamber and connected thereto by a plurality of ports, and ports for admitting the fluid acted upon to the inner ends of said passages, the active liquid upon rotation of the member being impelled by centrifugal force through the passages to force the liquid therefrom and into said chamber.

7. In combination, a casing having a main

4
chamber and a compression chamber, a rotary member within the main chamber having passages which discharge into the compression chamber, means for admitting a 5 stream of active liquid to the passages and removable sealing rings attached to the rotary member and frictionally engaging the walls of the main chamber for preventing communication from the compression chamber to the main chamber.

8. In combination, a stationary casing, a main chamber therein, a compression chamber in the casing communicating with said main chamber, a reservoir in the casing located above and communicating with the main chamber, a rotary member in said main chamber having radiating passages opening directly into the compression chamber, and means on said rotary member frictionally engaging the walls of the said main chamber for making an air tight joint therewith.

9. In a device of the class described, a casing, a reservoir in said casing, a main 25 chamber in said casing below said reservoir, a compression chamber in said casing, a collection chamber in said casing communicating with said compression chamber, a rotary member in said main chamber having 30 radiating passages leading directly to the

compression chamber said rotary member making an air tight joint with the interior of said main chamber, and a conduit between said collection chamber and said reservoir.

10. A device as specified in claim 9 having 35 a water jacket in the casing surrounding the compression chamber.

11. In combination a casing, a main chamber in the casing, a reservoir in the casing above said main chamber and communicating therewith, means for regulating the flow of fluid between the said reservoir and said main chamber, a rotary member in said main chamber having radiating passages and making an air tight joint with the peripheral wall of the main chamber, a compression chamber in said casing into which said 40 passages open, a collection chamber in the casing communicating with said compression chamber and located below said compression 45 chamber and a conduit between said collection chamber and said reservoir.

In testimony whereof I have hereunto set my hand in presence of two subscribing witnesses.

EDWARD C. D'YARMETT.
